Primary Examiner — Lauren D McVey

(57) **CLAIM**

The ornamental design for a hand stamping pressure tool, as shown and described.

DESCRIPTION

FIG. 1 is a top perspective view of a first embodiment of a hand stamping pressure tool showing my new design;

FIG. 2 is a top plan view thereof;

FIG. 3 is a bottom plan view thereof;

FIG. 4 is a first side elevation view thereof;

FIG. 5 is a second side elevation view thereof;

FIG. 6 is a third side elevation view thereof;

FIG. 7 is fourth side elevation view thereof;

FIG. 8 is a top perspective view of a second embodiment of the hand stamping pressure tool showing my new design;

FIG. 9 is a top plan view thereof;

FIG. 10 is a bottom plan view thereof;

FIG. 11 is a first side elevation view thereof;

FIG. 12 is a second side elevation view thereof;

FIG. 13 is a third side elevation view thereof; and,

FIG. 14 is fourth side elevation view thereof.
